UNITED STATES PATENT OFFICE.

GEORGE JOHNSON, OF SCRANTON, PENNSYLVANIA.

DESIGN FOR A DISPLAY STAND.

Application filed November 8, 1928. Serial No. 28,799. Term of patent 7 years.

To all whom it may concern:

Be it known that I, GEORGE JOHNSON, a citizen of the United States, residing at Scranton, in the county of Lackawanna and State of Pennsylvania, have invented a new, original, and ornamental Design for Display Stand, of which the following is a specification, reference being had to the accompanying drawing, forming a part thereof.

The figure is a perspective view of a display stand showing my new design.

I claim:

The ornamental design for a display stand, as shown.

GEORGE JOHNSON.
